UNITED STATES PATENT OFFICE.

EFFINGHAM H. WARNER, OF STORM LAKE, IOWA.

STEAM HEATING AND COOKING APPARATUS.

SPECIFICATION forming part of Letters Patent No. 431,130, dated July 1, 1890.

Application filed January 22, 1890. Serial No. 337,691. (No model.)

To all whom it may concern:

Be it known that I, EFFINGHAM H. WARNER, a citizen of the United States, residing at Storm Lake, in the county of Buena Vista and State of Iowa, have invented certain new and useful Improvements in a Steam Heating and Cooking Apparatus, of which the following is a full, clear, and exact description, that will enable others to make and use the same, reference being had to the accompanying drawings, forming a part of this specification.

This invention relates to an improved device that is more especially intended for domestic purposes; and it consists of certain novel features in the construction, combination, and arrangement of the different parts, as will be hereinafter set forth.

Figure 1 is a vertical section of an apparatus embodying my improved features; Fig. 2, a horizontal section in plane 2, Fig. 1; and Fig. 3, a horizontal section in plane 3, Fig. 1, both views looking in the direction indicated by the arrows.

Referring to the drawings, A represents a boiler or steam-generator, which is of a cylindrical form and without flues; A', the combustion-chamber or fire-box, and B a jacket inclosing the boiler and combustion-chamber. The boiler is provided with an auxiliary or secondary annular jacket C, which incloses the lower half of the same, being riveted thereto at a and extending downwardly therefrom to a point below the bottom thereof, as shown in Fig. 1. This auxiliary jacket occupies about one-half of the annular space a' between the boiler and the exterior jacket B. The annular space between the auxiliary jacket and the boiler forms the chamber a², for the purpose of utilizing all or nearly all of the heat rising from the combustion-chamber. The heated air ascends into the chamber a² and passes around both sides of the boiler, as indicated by the arrows in Figs. 1 and 2, and escapes

45 through the apertures a³ a⁴ in the auxiliary jacket into the space between the boiler and the exterior jacket, (see Fig. 2,) and then returns by passing around to the right and left, as indicated by the arrows in Fig. 3. 50 The heated air is thus returned to that side of the boiler from which it started, thereby

greatly increasing the area of the heating-surface, while the products of combustion finally escape into the smoke-flue a⁵, located at the opposite side from the apertures a³ a⁴ 55 in the auxiliary jacket. The position of these apertures is also indicated by dotted lines in Fig. 1. The boiler is supported on a number of angular brackets a⁶, bolted to the interior of the exterior jacket B. 60

When the apparatus is to be used for supplying live steam for heating or cooking purposes, the boiler is partially filled with water, the steam being conducted through the pipe D to the desired point. The water-pipes D' D² are respectively inserted in the boiler near the top and bottom and connect with the water-tank E. By filling the boiler full of water a water circulation is obtained and the contents of the tank heated, the 65 valve b in the steam-pipe being closed, as are also the valves b' b² in the water-circulating pipes when the boiler is to be used for steaming purposes.

The pipe F and valve d provide means for 70 drawing off the water down to the proper level when the boiler is to be used in generating steam.

G represents the usual safety-valve.

A hydrocarbon-burner H is shown in position in the combustion-chamber, and connects with the oil-tank d' by means of the supply-pipe d². It is obvious, however, that any other suitable means may be employed in generating the necessary heat. This arrangement provides a simple and convenient apparatus, which may be readily converted from one function or purpose to the other, requires but little care or attention, can be used with perfect safety in any house, and 85 with a small expenditure of fuel will supply 90 all the steam heat and hot water required.

Having thus described my invention, what I claim, and desire to secure by Letters Patent, is—

1. The combination, with the boiler or generator, of an auxiliary jacket inclosing the lower half of the generator and having an annular space between the two for the circulation of the heated air, and having openings 95 at one side for the escape of the heat into the space between the auxiliary and the exterior

jacket, substantially as and for the purpose set forth.

2. The combination of the generator, the exterior jacket, the angle-bracket supporting the generator, the auxiliary jacket located in the space between the exterior jacket and the generator and provided with openings for

the escape of the heated air at a point opposite to the exit-flue, substantially as and for the purpose set forth.

EFFINGHAM H. WARNER.
